CARBONIZER

Rudolph J. Hillstrom, Marshfield, Oreg.

Application December 1, 1928, Serial No. 323,075

3-Claims. (Cl. 202—124)

While I have designated my device as a carbonizer I do not limit its application, for it may be used as a dryer for carbonaceous materials and other non-carbonaceous materials, such as sand, and it might be used as a cooler also. Throughout my specifications I shall refer to it as a carbonizer.

My carbonizer is of the gravity feed progressive heating type and readily adapted for use with carbonaceous materials of widely separated characteristics. It is particularly adaptable to the carbonization of sub-bituminous coals of the non-coking type because the usual waste in slack may be utilized. In other words, for every ton of coal of the above type sold an extra quarter ton is mined and usually wasted. Many of the disadvantages of the use of slack in other processes are eliminated in my carbonizer as will become apparent as I describe it.

The advantages obtained with my carbonizer over the prior art are many. I have a carbonizer of extremely simple design and large capacity coupled with a low first cost, a low maintenance cost, and a low operating cost. The results obtainable are many and varied and are had without additional equipment. Two materials such as coal and sawdust may be run through together and come out perfectly mixed. The char may come from the carbonizer cooled off or it may come out heated to the proper degree for use in a briquetting machine. Oils of any desired boiling point may be taken off without their being subject to higher heat and without their being mixed with hotter gases evolved at hotter stages, thus eliminating secondary reactions. My carbonizer lends itself to use in a plant of any desired capacity either in size or control of the desired objectives.

The carbonizer as illustrated in the accompanying drawings is adapted for use in batteries which may be extended at will without revamping a layout. It is such that any desired gas or vaporized oils may be taken off from a carbonizer of any capacity by regulating the number of gas-collecting hoods.

I accomplish the objects set forth above in the carbonizer whose description follows and which is illustrated by the following drawing of which Fig. 1 is a vertical section thru a single unit; Fig. 2 is a vertical section thru a battery of two.

Similar numerals refer to similar parts throughout the several views.

My carbonizer is one in which the material or materials being treated flow downwardly by

gravity in a thin layer from the intake end of the carbonizer to the discharge end and in so doing are continuously heated and mixed by having their direction of flow frequently changed as they pass over heated, inclined and staggered, 5 baffling surfaces.

The material to be carbonized is discharged by any suitable means into the top of the carbonizer. I have shown it as being discharged from a conveyor 1, through the spout 2, into the hopper 3 formed as part of the carbonizer. The method of loading the hoppers is no part of my invention and is made to meet the conditions of the particular plant layout. The drawing shows the carbonizer built over a hopper 4 having a lower discharge. For purpose of description only this hopper is shown as being adapted to discharge the char, as for instance into a briquetting machine mixer, not shown. This feature is no part of my invention either and is merely shown and cited to show the adaptability of my carbonizer to economical layouts. This too, like the feeding arrangement, is governed by the particular plant. The carbonizer may be supported in any suitable manner. The shell of the carbonizer is rectangular in horizontal cross section and includes the side walls 5 and 6 and two end walls 7, only one of which appears in Figs. 1 and 2. Within this rectangular shell are one or more carbonizing chambers 8. Fig. 1, shows one carbonizing chamber 8 and Fig. 2, two. Each carbonizing chamber 8 lies between the corrugated walls 9 and 10 which are interposed between and connect with the end walls 7, which I space about three feet apart, in any suitable manner, no particular connection being shown. In Fig. 1, the wall 9 is spaced from the wall 5 to form the combustion chamber 11 and the wall 10 is spaced from the wall 6 to form the combustion chamber 12. In the battery formation shown in Fig. 2, the wall 10 of one carbonizing chamber 8 is spaced from the wall 9 of the adjacent carbonizing chamber 8 to form the combustion chamber 13.

The construction of the carbonizer is made so as to confine the products of combustion to the combustion chambers 11, 12, and 13, thereby preventing them from mingling with the material being treated within the carbonizing chambers 8. Heating gases, moving upwardly pass from the combustion chambers 11, 12, and 13, by way of the openings 14 into the atmosphere, into a chimney, or to an auxiliary drier, neither the chimney or drier being shown. When discharging into the atmosphere, conditions sometimes warrant the use of a fan, not shown, for creating an in-

duced draft. Hot gases are supplied by the gas burners 15 placed within the combustion chambers 11, 12, and 13, and adjacent each corrugation 16, if desired, and so as to more directly 5 act upon the surface 16A, of said corrugations 16, over which the material being distilled passes. The walls 9 and 10 forming the carbonizing chamber 8 are made continuous from the intake end of 10 the carbonizer to the discharge valve 17, their 15 connections with the hopper 3 and the walls 5, 6, and 7, being made gas-tight.

The lower end of the carbonizing chamber 8 is 15 closed by the rotary discharge valve 17 by which the movement of material thru the carbonizing chamber 8 is controlled. To operate this valve 17 I have used, per unit, a $\frac{1}{2}$ H.P. motor, suitably geared and controlled. The motor, gearing, and control, I have not shown.

It will be noted that the corrugations 16 of 20 the wall 9 are arranged in staggered relation to the corrugations 16 of the wall 10. By the staggered arrangement of the corrugations, I can constrict the throat, thru which the material being treated passes, as at the point 18 and thus form 25 an enlarged portion 19, in which, preferably, I insert an inverted approximately V-shaped hood 20 under which the gases collect and from which they are led through the vapor and gas outlets 21 from the carbonizer directly to the exterior. 30 The gases do not pass thru heated zones because the approximately V-shaped hoods 20 extend between and are connected to the walls 7 in any suitable manner, no particular connection being shown. The vapor and gas outlets 21 are positioned in either or both of the walls 7.

With the sub-bituminous coals of the Coos Bay district I find that if I make the angle of the sides of the corrugations 16 an angle of 35 50 degrees and leave a $1\frac{1}{2}$ " space between the corrugations 16 at the point 18 everything works well. I have had no trouble with the coal clogging. While this angle may be made 50 degrees with Coos Bay coals it is to be understood 40 that it must always be greater than the angle of repose for the materials being treated. For the coals mentioned I find the use of twenty-four of the hoods 20 to be satisfactory, although I have shown a lesser number in my drawing. With the twenty-four hoods 20 I get a sufficiently fast carbonizer to make char for briquetting and to recover the oils I wish to obtain. While I find twenty-four satisfactory for my purpose, the number of hoods 20 is made in accordance 45 with the capacity of the plant and the objectives sought. I have placed the sides of the approximately V-shaped hoods 20 parallel with the adjacent sides of the corrugations 16 and spaced $1\frac{1}{2}$ " therefrom. The sides of the corrugations 16 are made long enough that length 50 may be given to the sides of the approximately V-shaped hoods 20 so that a good seal may be formed by the coal passing through whereby gases liberated adjacent a particular hood 20 may be confined therein. The cross sectional 55 area of a hood 20 is so much larger than that of the vapor and gas outlet 21 that the gas may be taken away from the coal at a low velocity, thus materially reducing the amount of dust drawn over with the gas. Because each hood 60 20 is sealed from the others by the coal, it is possible to withdraw all gaseous products by suction.

Thru the intake pipes 22, water is admitted to the combustion chambers 11, 12, and 13. The height to which the water may rise in the

chambers is fixed by the overflow pipes 23, said overflow pipes 23 permitting a circulation of the water.

I shall now proceed to describe the operation of the carbonizer in order to more clearly point out its many advantages and its simple operation. 5

We will assume that the coal is of the proper size to feed through the carbonizer and is delivered by the conveyor 1 and discharged by the 10 spout 2 into the hopper 3 connected with the upper ends of the walls 9 and 10 forming the sides of the carbonizing chamber 8. The hopper 3 is so constructed as to allow sufficient coal, usually several feet, to form a good seal over the 15 top hood 20. The coal slides down in an even thin layer over a side 16A of a corrugation 16 of the wall 9 onto a side 16A of a corrugation 16 of the wall 10 and so on down over all the corrugations 16 to the discharge valve 17. Part 20 of the coal is deflected by the inverted approximately V-shaped hoods 20 and passes through the space between the side 20A of said hood 20 and the side 16B of the adjacent corrugation 16. The downward movement of the coal is controlled by the discharge valve 17 at the will of the operator.

Gas stored from a previous run is fed to the lower burners 15 to start the operation. After 25 gas begins to form in the carbonizer it is fed to the burners 15 so that the carbonizer supplies its own fuel for heating the walls 9 and 10 enclosing with the end walls 7 the carbonizing chamber 8. If it were desired these walls might be heated by electric grids or heat might 30 be generated and delivered to the combustion chambers 11, 12, and 13, at a point above the overflow pipes 23 from a gas-fired extended fire box. I have only illustrated the gas burners, these being the preferred means to supply heat 35 to the walls 9 and 10. Thru their use heat may be localized at desired points. Regardless of the method employed the heat travels upward and progressively heats the coal moving downward over the heated surfaces of the corrugations 16 40 of the walls 9 and 10 forming sides of the carbonizing chamber 8. Naturally the coal becomes hotter as it gets toward the discharge end. Moisture and the lighter oils start to distill over from the coal toward the top, filtering out through the 45 moving coal and into the adjacent approximately V-shaped hoods, and those of a higher boiling temperature in a similar manner lower down where they collect and from which they are led through the vapor and gas outlets 21 for 50 further processing in other devices not a part of this invention. There is no dilution of gases from the heating medium nor from those of a higher temperature. As the coal reaches the corrugations 16 below the overflow pipes 23 it is 55 cooled by the water in the lower portions of the chambers 11, 12, and 13. Whether it is desirable to cool the char depends entirely upon the objectives sought. Thru the control of the rotary valve 17 and the number of gas burners 60 put in operation, the rate and degree of carbonization may be readily controlled.

From the above description and from a perusal of the drawing, it will be seen that I have perfected a carbonizer of extreme simplicity both in 70 first cost, maintenance, and operation; one in which the coal constantly mixes itself as it moves downwardly by gravity in such a thin uniform layer as will absorb the maximum heat from the corrugated walls of the carbonizing chamber; one 75

in which the only moving element is the small rotary char-discharging valve 17; one in which the coal is progressively heated; one in which vaporized oil, for instance, distilling in a narrow boiling range is liberated and kept from dilution with other oils of different boiling points; and one in which this fractionating feature may be controlled for the objectives sought.

Having described my invention and illustrated it so clearly that anyone skilled in the art of low-temperature carbonization of coal or other carbonaceous substances might build an operable plant, I claim:

1. In a carbonizing apparatus, in combination:
  - 15 a vertical shell having a carbonizing chamber therein, said carbonizing chamber having a plurality of alternate expanded and contracted portions; V-shaped hoods within the expanded portions adapted to change the direction of flow of coal passing through the carbonizing chamber; vapor and gas offtakes within the hoods; a coal hopper attached to the top portion of the shell and adapted to admit coal to the carbonizing chamber; a water jacket externally attached to the lower portion of the carbonizing chamber for cooling the carbonized residue; flow-control means in the lower portion of the shell for withdrawing the cooled carbonized residue; and burners located within the shell adjacent the contracted portions of the carbonizing chamber.
  - 20
  - 25
  - 30
  - 35

chamber having a plurality of alternate expanded and contracted portions; V-shaped hoods within the expanded portions adapted to change the direction of flow of coal passing through the carbonizing chamber; vapor and gas offtakes within the hoods; a coal hopper attached to the upper ends of the corrugated walls and adapted to admit coal to the carbonizing chamber; flow control means in the lower portion of the shell for withdrawing carbonized residue; and burners located within the combustion chambers adjacent the contracted portions of the carbonizing chamber.

3. A carbonizer unit comprising a vertical shell; two corrugated walls set in staggered arrangement positioned within the shell and extending between opposite shell walls and spaced apart and each spaced from the adjacent shell walls and forming a centrally positioned carbonizing chamber and flanking combustion chambers, said carbonizing chamber having a plurality of alternate expanded and contracted portions; V-shaped hoods within the expanded portions adapted to change the direction of flow of coal passing through the carbonizing chamber; vapor and gas offtakes within the hoods; a coal hopper attached to the upper ends of the corrugated walls and adapted to admit coal to the carbonizing chamber; a water jacket, occupying the lower portion of the combustion chambers, for cooling the carbonized residue; flow-control means in the lower portion of the shell for withdrawing the cooled carbonized residue; and burners located within the combustion chambers above the portion containing the cooling water and adjacent the contracted portions of the carbonizing chamber.

RUDOLPH J. HILLSTROM.
